UNITED STATES PATENT OFFICE

WILLIAM S. ASHTON, OF WATERTOWN, MASSACHUSETTS, ASSIGNOR TO THE B. F. GOODRICH COMPANY, OF NEW YORK, N. Y., A CORPORATION OF NEW YORK

LAST SUPPORTING DEVICE

Application filed August 14, 1930. Serial No. 475,162.

My invention relates to last jacks or supports for use in the manufacture of boots and shoes.

The improved jack is particularly useful in adjustably supporting a boot last during the assembling of various parts which must be associated on the last and rolled into adhering contact therewith, and is especially adapted for use in connection with the manufacture of boots on a traveling conveyor.

The chief object of my invention is to provide in an improved manner for supporting a boot last so that it extends substantially in a horizontal direction from a conveyor and is so supported that it may be readily adjusted and locked in a plurality of determinate positions while boot-making operations are performed upon it.

Another object is to provide improved means for positively supporting the last in a plurality of positions so that it will not be displaced by downwardly directed forces applied to the last in the building operations.

A further object is to provide means for positively locking the last to the support.

Other objects will be apparent from an examination of the drawings and following description.

In the accompanying drawings:

Fig. 1 is a side elevation of the last jack mounted on a conveyor, the conveyor being shown in section and the last being shown in one of its positions in full lines, with portions broken away, and in another position in dot and dash lines.

Fig. 2 is an enlarged sectional view of parts of the last and jack illustrating the last-locking and indexing mechanism.

Fig. 3 is a cross section on line 3—3 of Fig. 1 showing the conveyor in elevation, parts being sectioned and broken away, and

Fig. 4 is a section on line 4—4 of Fig. 1.

Referring to the drawings, 1 is a conveyor carriage mounted to travel between guide-ways 2, 2 and engaged by a conveyor chain 3. Mounted on the carriage 1 is a last jack comprising a supporting bracket 4, and an arm 5 pivoted thereto and formed with a horizontal bearing 5^a in which a last-supporting member 6 is mounted. The last-supporting

member is provided with a tapered extension 6^a adapted to fit an opening in the last.

The last support 6 is provided with a central bore in which is slidably mounted a rod 7 (see Fig. 2) formed at its end nearest the last with an extension 8 slotted as at 8^a. The end of the extension 6^a of the last support is slotted and carries a cross-pin 9 to which is pivoted a detent 10 which extends through the slot 8^a of the rod's extension 8. The other end of rod 7 is pinned to an enlarged head 11 slidably mounted in a counterbore in last support 6. A ratchet latch member 12 is pivoted at 13 to the head 11 and is located in a longitudinal slot therein and adapted to engage a catch plate 14 which is mounted on the head 11 and extends into the counterbore therein. A spring 15 holds the latch 12 and plate 14 in engagement except when opposed by a hand-operated cam lever 16 pivoted at 17 on the head 11. By means of the mechanism described, rod 7 may be moved longitudinally of the last-supporting member 6. On such movement in a direction to the left in Fig. 2 the detent 10 will be projected beyond the surface of the extension 6^a from its dotted line position of Fig. 2, and into engagement with the last as shown, the latch 12 engaging the catch 14 and locking the rod 7 in this position. To release the last the cam lever 16 is pushed to the right as viewed in Fig. 2, and depresses the latch 12, releasing it from the plate 14, and by further movement of the cam lever to the right the rod 7 is moved and the detent 10 is turned back to the position indicated in dotted lines in Fig. 2, whereupon the last may be removed.

In order that the last support, journaled in the arm 5, may be locked against rotation in determinate positions to facilitate the placing and rolling of the various pieces which make up the boot, it is formed with a circumferential groove 6^b from which extend laterally a plurality of recesses 6^c. A screw 18 is threaded through the journal 5^a and is provided with a smooth end portion which extends into the groove 6^b. The construction is such that, as shown in Fig. 2, the last support 6 may be rotated in the journal 5^a when the screw 18 is in the groove 6^b, but when desired

the last support may be urged to the right to cause the screw 18 to enter one of the pockets 6^c and thus lock the last support against rotation.

- 5 For supporting the arm 5 in determinate relation to the bracket 4, the bracket 4 is provided with an inclined slot 4^a and its outer extremity is formed with stepped shoulders 4^b and 4^c. Extension 5 is slotted so as to straddle the bracket 4 and is provided with a cross-pin 19 carrying a roller 20 which is mounted in the slot 4^a. The extension is so formed that a shoulder 5^b thereon is adapted to rest on shoulder 4^b when roller 20 is in the extreme outer position, and to rest on the shoulder 4^c, to hold the arm 5 in a higher position when the roller 20 is at its innermost position.

20 A cushioning device is provided on shoulder 4^b and consists of a plunger 21 backed by a spring 22 mounted in a barrel 23. The plunger 21 is shouldered so as to provide a stop against over-movement in an outward direction and a screw 24 provides means for 25 adjusting the spring tension and allows removal of the spring and plunger.

What I claim is:

1. A last jack comprising a bracket provided with a plurality of shoulders, an arm 30 pivoted to said bracket and adapted to be selectively supported on said shoulders at a plurality of elevations, and last-supporting means mounted on said arm.

2. Apparatus as defined in claim 1 including cushioning means associated with one of the shoulders.

3. Apparatus as defined in claim 1 in which the last supporting means is journaled in said arm for rotation about a horizontal axis and 40 may be locked against rotation in a plurality of positions.

4. Apparatus as defined by claim 1 in which the last-supporting means is provided with a tapered dowel for engaging in a corresponding opening in the last, and includes means extending through said dowel and cooperating therewith for locking the last to said supporting means.

In witness whereof I have hereunto set my hand this 1st day of August, 1930.

WILLIAM S. ASHTON.
